ATTORNEY

UNITED STATES PATENT OFFICE

134,709

DESIGN FOR AN EMBROIDERED FABRIC OR THE LIKE

Anton Walter, New York, N. Y.

Application December 3, 1942, Serial No. 108,943

Term of patent 3½ years

To all whom it may concern:

Be it known that I, Anton Walter, a citizen of the United States of America, residing in New York city, county of New York, and State of New York, have invented a new, original, and ornamental Design for an Embroidered Fabric or the like, of which the following is a specification, reference being had to the accompanying drawing, forming part thereof, wherein the figure of the drawing is a plan view of an embroidered fabric or the like showing my new design.

I claim:

The ornamental design for an embroidered fabric or the like, substantially as shown.

ANTON WALTER.
